UNITED STATES PATENT OFFICE.

ROSE LUCAS ALLEN, OF HOWARD, PENNSYLVANIA.

DESIGN FOR A HANGING VASE.

SPECIFICATION forming part of Design No. 13,297, dated September 19, 1882.

Application filed July 24, 1882. Term of patent 3½ years.

To all whom it may concern:

Be it known that I, ROSE L. ALLEN, of Howard, in the county of Centre and State of Pennsylvania, have invented a new and Improved 5 Design for Hanging Vases, of which the following is a full, clear, and exact description.

Figure 1 is a perspective view of my newly-designed vase with its drip-cup attached, and Fig. 2 is a plan view of the drip-cup.

10 Similar letters of reference indicate corresponding parts.

The leading feature of my design consists in the production of a vase which shall present the outward appearance of being made up of 15 leaves, the drip-cup being in the form of a single large leaf.

In the drawings, A is the body of the vase, which may be made in any desired form, but which is preferably saucer-shaped, as shown. 20 Upon the outside of the body A, and formed with it, are the oak or other leaves a, six in number, which are arranged upon the body so that their petioles will meet under the body at or near the center, and so that the upper ends of 25 the blades will reach above the upper edge of the body A, as shown. Though this is the preferred arrangement of the leaves upon the vase, it is obvious that other arrangements might be adopted and not depart from the 30 main feature of the design; and, instead of imitating six leaves upon the outside of the body, a greater or less number may be imi-

tated, as desired, or according to the kind of leaf selected for imitation.

Suspended from and under the vase by the 35 cords b is the drip-cup B, which is also saucer-shaped, and is formed in imitation of a large leaf, as represented in Fig. 2.

The vase and drip-cup may be made of clay, 40 bronze, or any other suitable material.

The vase is adapted to be suspended by the cords e, and when thus suspended with the drip-cup B suspended under it the whole presents to the eye the appearance clearly represented in Fig. 1.

Having thus fully described my invention, I 45 claim as new and desire to secure by Design Patent—

1. A design for a vase, consisting of leaves arranged upon the outside of the body with 50 the petioles meeting under and at or near the center of body and the upper ends of the blades reaching above the upper edge of body, as shown and described.

2. The design for a vase and drip-cup here- 55 in shown and described, the same consisting of the saucer-shaped body A, having the imitation of leaves a formed upon its surface, and the suspended saucer-shaped cup B, made in imitation of a large leaf.

ROSE LUCAS ALLEN.
